UNITED STATES PATENT OFFICE

112,206

DESIGN FOR A COMBINED TRAY AND RECEPTACLES FOR SMOKERS

John K. Milton, Chicago, Ill.

Application June 18, 1938, Serial No. 77,918

Term of patent 3½ years

To all whom it may concern:

Be it known that I, John K. Milton, a citizen of the United States, residing at Chicago, in the county of Cook and State of Illinois, have invented a new, original, and ornamental Design for a Combined Tray and Receptacles for Smokers, of which the following is a specification, reference being had to the accompanying drawing, forming part thereof, in which:—

Fig. 1 is a perspective view of a combined tray and receptacles for smokers showing my new design and tilted forward to foreshorten the two vessels at the sides of the medial column, which are of regular octagonal form; and

Fig. 2 is an elevational section taken on the line 2—2 of Fig. 1.

I claim:

The ornamental design for a combined tray and receptacles for smokers, as shown and described.

JOHN K. MILTON.
